ROLLER APPLICATORS FOR LIQUIDS
 James A. Fugate, 1239 S. Sandusky, Tulsa 12, Okla.
 Filed Aug. 16, 1961, Ser. No. 131,813
 17 Claims. (Cl. 15—548)

The present invention relates to a roller type device for applying a liquid to a surface to be coated and the invention more specifically pertains to a roller applicator for applying paint to a wall or the like wherein the liquid is supplied through the interior of the roller to the outer shell by a pump assembly or pump means arranged within the roller which serves to move liquid from a supply or reservoir to the perimeter of the roller.

It is known to force liquid such as paint into the interior of a roller type applicator by means of compressed air developed in a pressure supply tank for the paint or the like. As distinguished therefrom the present invention is directed to pump means incorporated within the roller itself which is set in operation by rotation of the roller to deliver liquid from a supply or a container into the roller and into the presence of the outer shell for transfer onto a surface to be coated.

An object of the invention is to provide pump means in combination with a roller type liquid applicator which functions to pump liquid from a supply or reservoir into the roller and to a position for being transferred from the outer shell of the applicator onto surface to be coated.

Another object of the invention is to provide a roller type device for applying a liquid to a surface with a pump mechanism within the roller driven by rotation of the roller applicator with the pump elements so arranged as to avoid enlarging the size of the roller and without materially increasing the weight of the applicator and with elements of the pump means being readily dismantled to facilitate cleaning of the parts which are subjected to the presence of the liquid or paint.

A further object of the invention is to provide means for controlling the quantity or rate at which the liquid is moved by the pump means into the roller.

Other objects and features of the invention will be appreciated and become apparent to those skilled in the art to which the invention pertains as the present disclosure proceeds and upon consideration of the following detailed description taken in conjunction with the accompanying drawing wherein several exemplary embodiments of the invention are disclosed.

In the drawing:

FIG. 1 is a side elevational view of a roller liquid applicator embodying the invention and illustrating a container for a supply of liquid with a flexible conduit extending therefrom to the applicator.

FIG. 2 is an enlarged axial sectional view of the roller and pump assembly of FIG. 1.

FIG. 3 is a transverse sectional view taken on the line 3—3 of FIG. 2.

FIG. 4 is an axial sectional view of a roller applicator with the pump elements of the combination constituting a modification.

FIG. 5 is an enlarged sectional view of the valve structure associated with the supply line for controlling the volume of liquid delivered into the roller.

An applicator embodying the invention has particular utility for applying paint to walls or the like and the roller and pump mechanism avoids the necessity of dipping the applicator into a supply of paint. The paint applying roller with the pump means incorporated therein functions to draw paint from a container holding a supply of liquid and deliver it into the roller and to the outer shell of the roller by the manual maneuvering of the applicator and by causing the periphery of the device to roll on the surface to be painted.

2

The assembly is desirably constructed to be portable and a handle 10 adapted to be gripped by the hand of an individual has an opening therethrough for receiving and supporting a straight portion 11 of a tube 12 which is substantially rigid and may be formed of metal. The handle is aligned with a mid-portion of a roller assembly 14 and it is for this purpose that the tube 12 has angular portions and an end portion 16 remote of the handle which is straight and serves as a hollow stationary shaft for the roller as hereinafter described. The paint or other liquid may be stored in a container 17 which is connected by a flexible conduit or hose 18 to the tube portion 11 in any suitable manner and preferably at the free end of the handle 10. The container 17 may be formed of flexible material and provided with a sling or strap 19 for supporting the container with a supply of liquid therein from the shoulder or the neck of an operator. The container 17 may be of such construction that the liquid or paint is not exposed to the atmosphere whereby the liquid is completely encased from the supply to the interior of the roller assembly 14.

A mechanism or means for delivering liquid from the container 17 into the interior of the roller assembly 14 is shown in FIGS. 2 and 3. The roller structure which also forms parts of the pump mechanism includes an elongated tubular member 21 which is substantially cylindrical shaped. The member 21 is provided with an annular recess on the periphery thereof throughout the length thereof except for end lips 22. The recess provides an annular space 23 between the perimeter of the member 21 and a conventional textile type outer shell 24 having interstices or openings 25 through the web portion so that the liquid may pass to the elements 26 which serve to transfer the liquid onto the surface to be treated.

The member 21 is adapted to rotate about the axis of the straight portion 16 of the tube 12. A substantially disc-shaped member 27 is carried by the shaft portion 16 of the tube and the periphery of the disc-shaped member 27 serves as a bearing support for one end portion of the member 21. A transverse web or partition 28 which may be formed integral with the member 21 has an axial opening therethrough for accommodating the free end of the hollow shaft 16 and this part of the shaft serves to support another portion of the member 21 for rotation. Gasket means 29 may be provided to prevent leakage of the liquid through the journal opening in the partition 28.

The member 27 is secured to the shaft portion 16 of the tube in fixed relationship or formed integral therewith so that it remains stationary and fixed with respect to other elements of the assembly. One or more pins 31 extend in parallel relationship from the member 27 and substantially parallel to the shaft portion 16 as shown in FIG. 2. A cylinder is formed within the intermediate portion of the member 21 and the bore of the cylinder is indicated at 30. The cylinder is closed at one end by the partition 28. A piston 32 is mounted for reciprocating movements within the cylindrical bore 30. The piston 32 is slidable on the straight shaft portion 16 of the tube 12 and carries a gasket means at its perimeter and around the straight shaft portion 16 of the tube to prevent leakage of liquid from the chamber 34. The member 21 beyond and spaced from the cylinder bore 30 is provided with coarse threads 37 which have a high pitch. A disc-shaped element 38 is connected to the piston 32 by a tubular element 39 to provide a plunger member. The exterior of the element 38 is provided with threads 41 engageable with the threads 37.

During rotation of the roller member 21 the threads 37 turn therewith but the element 38 is retained from rotation by means of the pins 31 which extend through openings in the disc element 38. Accordingly the plunger and

the piston 32 moves axially with respect to the shaft portion 16 of the tube 12. In one embodiment the threads 41 escape from the end of the threads 37 after approximately four revolutions of the roller member 21. The assembly includes resilient means urging the plunger member including the disc element 38 to a position for reengaging the threads 37 when rotation of the roller member 21 is reversed. Such resilient means may take the form of a helical spring 42 arranged within the chamber 34 and surrounding the hollow shaft 16 with one end abutting 10 the partition 28 and the other end abutting the piston 32. Another spring 43 or resilient means surrounds the hollow shaft 16 with one end in abutting relationship with the disc element 38 within a cavity therein while the other end of the spring 42 abuts the member 27 within a confronting 15 cavity.

A plurality of radially disposed holes or discharge ports 46 are provided through the roller member 21 with the inner ends thereof in communication with the cylinder chamber 34. In operation liquid is forced outwardly through these holes into the annular space 23. Valve means for the discharge ports 46 may take the form of an elastic band 47 which surrounds the member 21 and overlies the exit ends of the holes 46. A plurality of inlet ports or opening 48 are provided through the wall of the hollow shaft 16 within the chamber 34. Liquid is drawn into the cylinder chamber 34 through the openings 48 during the suction stroke of the pump and valve means which may take the form of an elastic or rubber band 49 overlies the exit ends of the ports 48 and serves to prevent the return of the liquid from the chamber 34 into the tube 12 during the expulsion stroke of the piston 32.

The combination is assembled by introducing the piston 32 and the plunger member into the cylinder bore 30 and thereafter the member 21 with the elastic band and the outer shell theron is moved to the right in FIG. 2 over the hollow shaft portion 16 until the shoulder 51 on the member 21 engages the disc member 27. The opening of the partition 28 then accommodates the free end of the hollow shaft portion 16 of the tube. A retaining member 52 is then arranged within the end of the member 21. The retaining member is provided with wings 53 for rotating a threaded inner end 54 into threaded engagement with threads carried by the interior of the hollow shaft 16. An annular shoulder 56 on the retaining member serves as an abutment to maintain the shoulder 51 in operative relationship with the inner face of the disc member 27 and to retain the partition 28 in operative association with the free end of the hollow shaft 16.

In operation and during rotation of the roller member 21 in one direction the plunger is moved to the right in FIG. 2 to develop suction in the tube 12 and to draw liquid from the container 17 through the conduit 18 and the tube 12 into the chamber 34 through the openings 48. During the suction stroke the elastic band 49 is distended outwardly. Continued rotation of the roller member 21 and the outer shell carried thereon in the same direction causes the threads 41 to escape from the threads 37 and this completes the suction stroke. During such movement the spring 43 is compressed and the threads 41 are held in position to reengage the threads 37 upon rotation of the member 21 in an opposite direction. In carrying out a paint applying or coating operation the roller is manipulated manually and the member 21 takes up rotation in a direction opposite to that just described. The element 38 is then shifted to the left compressing the spring 42 and the piston 32 moves to the left in FIG. 2 forcing the liquid trapped in the chamber 34 outwardly through the discharge holes 46 and into the annular recess or space 23. The elastic band 47 yields to permit the escape of the liquid from the chamber 34 and serves as a valve preventing the return of the liquid inwardly through the discharge holes 46. The spring 42 is compressed and the energy stored therein during the expulsion stroke of the plunger member maintains the disc element

38 in position to reengage the threads 37 upon rotation of the member 21 in the first described direction.

A modification is shown in FIG. 4 wherein a diaphragm 56 replaces the piston 32 and the gaskets associated therewith. In this embodiment the disc member 27a is provided with an annular extension 57 which forms a larger bearing surface for the member 21a. The annular extension 57 carries the threads 37 which remain stationary because the member 27a is carried by the hollow shaft 16 in fixed relationship. The periphery of the diaphragm 56 is clamped between a shoulder 58 formed on the member 21a and the end 59 of a ring member 61. The ring member 61 is in abutting relationship with the end of the annular extension 57 and upon tightening of a retaining member 52a the perimeter of the diaphragm 56 is sealed with respect to the member 21a and the ring member 61. A key 62 carried by the member 61 extends into an axially disposed groove 63 in the tubular element 39a. The key 62 provides a driving connection between the member 21a and the tubular element 39a. Thus the disc shaped element 38a is rotated to shift the tubular element 39a axially on the hollow shaft. The inner circumference of the diaphragm 56 is clamped to and maintained in sealed relationship with the end of the tubular element 39a and the perimeter of the hollow shaft 16. The diaphragm 56 has resilient characteristics so that when the inner portion is deformed axially of the chamber 34 it serves to urge the tubular element 39a and the disc element 38a in an opposite direction so that the threads 41 are in a position to reengage the threads 37.

In this embodiment the device is assembled by arranging the disc element 38a in a neutral position with respect to the threads 37. The ring member 61 is then applied with its end in abutting relationship with the free end of the annular extension 57 after the key 62 is in position within the groove 63. The member 21a is applied to the right in FIG. 4 until the shoulder 58 engages the perimeter of the diaphragm 56. The opening in the partition 28 then accommodates the free end of the hollow shaft 16. The retaining member 52a is then applied with the threaded end engaging the interior threads of the hollow shaft 16. A helical spring 66 serves to bias the member 21a to the right in FIG. 4 holding the elements in assembled relationship.

The pump means incorporated in the roller applicator shown in FIG. 4 functions in a manner similar to that described in connection with the first embodiment. The member 21a rotates about the annular extension 57 and the partition 28 rotates about the hollow shaft 16. The ring member 61 and the diaphragm 56 rotates with the member 21a. The key 62 extending into the groove 63 causes the tubular element 39a to rotate about the axis of the hollow shaft 16. The disc element 38a rotates in one direction causing the tubular element 39a to shift axially distorting the diaphragm 56 and creating a suction stroke drawing liquid into the chamber 34 through the inlet openings 48. The resilient character of the diaphragm 56 serves to maintain the threads 41 in position to reengage the threads 37. Thus upon reverse rotation of the member 21a the tubular element 39a is moved axially to provide an expulsion stroke of the pump means. Liquid is then forced from the chamber 34 through the discharge holes 46 into the annular space 23.

The assembly includes means in association with the supply line to control the quantity of liquid delivered by the pump means. Such means is shown generally at 68 in FIGS. 1 and 5 and provides for admitting controlled quantities of air into the tube 12 which is provided with an aperture 71. A valve housing 72 encases the tube 12 in the vicinity of the aperture 71. It is provided with interior threads 73 receiving exterior threads 74 on a stem 76. An axial passage 77 is provided in the stem in communication with a transverse passage 78. A cage 79 on the inner end of the stem 76 contains a ball 81 of smaller

diameter than the cage 79. When the stem 76 is adjusted to an outer position by turning the knob air is admitted through the passage 78 and the passage 77 around the ball 81 and through the aperture 71. The valve mechanism serves to prevent the outward flow of liquid from the tube 12 because the ball 81 then closes the cage in the area 82. The control valve of FIG. 5 may be employed with either modification and may be adjusted to admit limited quantities of air to the tube 12 and thereby control the quantity of liquid delivered by the pump means.

While the invention has been described with particular reference to a roller type applicator with pump means therein for delivering paint to the outer shell of such a device it will be appreciated that it may be used for other liquid applying purposes. Changes may be made in the structure of the roller as well as the pump elements. Such modifications and others may be made without departing from the spirit and scope of the invention as set forth in the appended claims.

What I claim and desire to secure by Letters Patent is:

1. A roller type applicator for liquids comprising in combination, a tube including a hollow shaft portion and a support portion extending angularly therefrom, a handle carried by said support portion, an elongated generally tubular shaped member supported by said shaft portion for rotation about the axis thereof, a previous shell embracing and carried by said member, means providing a chamber within said member, said member having discharge ports providing communication from said chamber to the periphery of said member, said shaft portion having inlet ports providing communication from the interior of said tube to said chamber, check valve means associated with said inlet ports, check valve means associated with said discharge ports, pump means within said member including means within said chamber moved by rotation of said member about the axis of said shaft portion to draw liquid into the chamber from within said tube through said inlet ports and expel it through the discharge ports into the presence of said shell, and said check valve means each consisting of an elastic band overlying the exit ends of the respective ports.

2. A roller type applicator for liquids comprising in combination, a liquid supply tube including a hollow shaft, an elongated substantially cylindrical shaped hollow member supported for rotation about the axis of said shaft, an outer shell embracing and carried by said member, a transverse partition within said member, means including said partition providing a chamber within said member around said shaft, said member having radially disposed discharge ports providing communication from said chamber to the periphery of said member, said shaft having inlet ports providing communication from the interior of said shaft to said chamber, check valve means associated with said inlet ports, check valve means associated with said discharge ports, pump means arranged about said shaft within said member including means acting within said chamber actuated by rotation of said member about the axis of said shaft to draw liquid into the chamber from within said tube through said inlet ports and expel it through the discharge ports into the presence of said outer shell, one of said check valve means consisting of an elastic band encircling said member overlying said discharge ports, and the other check valve means consisting of an elastic band encircling said hollow shaft overlying said inlet ports.

3. A roller type applicator for liquids comprising in combination, a liquid supply tube including a hollow shaft, an elongated substantially cylindrical shaped hollow member supported for rotation about the axis of said shaft, an outer shell embracing and carried by said member, a transverse partition within said member, means including said partition providing a chamber within said member around said shaft, said member having radially disposed discharge ports providing communication from

said chamber to the periphery of said member, said shaft having inlet ports providing communication from the interior of said shaft to said chamber, check valve means associated with said inlet ports, check valve means associated with said discharge ports, pump means arranged about said shaft within said member including means acting within said chamber actuated by rotation of said shaft to draw liquid into the chamber from within said tube through said inlet ports and expel it through the discharge ports into the presence of said outer shell, and valve means for admitting and controlling entry of air into said tube.

4. A roller type applicator for liquids comprising, a liquid guiding tube including a hollow shaft, a member carried by said shaft in fixed relationship therewith, a peripheral bearing surface on said member concentric with the axis of said shaft, an elongated generally tubular shaped member having a cylindrical inner surface rotatable on said bearing surface, a transverse partition within said tubular member spaced from said bearing surface and having a bearing surface rotatable on said shaft, a shell embracing the periphery of and carried by said tubular member, means including said partition providing a chamber within said tubular member, said tubular member having discharge ports from said chamber to the periphery of said tubular member, said shaft having inlet ports from the interior thereof to said chamber, check valve means associated with said discharge ports, check valve means associated with said inlet ports, a tubular element slidable on said shaft, means carried by said tubular element spaced from said partition closing said chamber, a disc element carried by said tubular element having threads thereon, mating threads on one of said members whereby said tubular element is moved along said shaft by rotation of the tubular member on said bearing surfaces to enlarge the volume of said chamber and draw liquid into the chamber from within said tube through said inlet ports and to reduce the volume of said chamber and expel the liquid through said discharge ports into the presence of said shell.

5. A roller type applicator for liquids according to claim 4 wherein the means closing the chamber includes a flexible diaphragm.

6. A roller type applicator for liquids comprising, a liquid guiding tube including a hollow shaft, a member carried by said shaft in fixed relationship therewith, a peripheral bearing surface on said member concentric with the axis of said shaft, an elongated hollow roller member having a cylindrical inner surface rotatable on said bearing surface, a transverse partition within said roller member having a central bearing surface rotatable on said shaft portion, means including said partition and a cylindrical bore providing a chamber within said roller member, said roller member having discharge ports from said chamber to the periphery thereof, said shaft having inlet ports from the interior of said tube to said chamber, an elastic band encircling said roller member overlying said discharge ports, an elastic band encircling said shaft overlying said inlet ports, a tubular element slidable on said shaft portion, a piston carried by said tubular element slidable within said bore, a disc element carried by said tubular element having threads on the periphery thereof, mating thread on the interior of said roller member, means restraining said disc element from rotation during sliding movements of said tubular element whereby said piston is moved by rotation of said roller member about said bearing surface to enlarge the volume of said chamber and draw liquid into the chamber from within said tube through said inlet ports and to reduce the volume of said chamber and expel the liquid through the discharge ports.

7. A roller type applicator for liquids according to claim 6 wherein the threads are of limited extent measured axially of the applicator, and resilient means urging the disc element to positions for reengaging the threads.

8. A roller type applicator for liquids according to claim 6 wherein the means restraining the disc element from rotation consists of pins carried by the first member which extend into openings in the disc element.

9. A roller type applicator for liquids comprising, a hollow shaft, a member having an open interior carried by said shaft in fixed relationship therewith, an elongated generally tubular shaped member rotatable about the axis of said shaft, a transverse partition within said tubular member, means including said partition providing a chamber within said tubular member, said tubular member having discharge ports from said chamber to the periphery thereof, said shaft having inlet ports from the interior to said chamber, check valve means associated with said discharge ports, check valve means associated with said inlet ports, an element slideable on said shaft, a resilient diaphragm carried by said element spaced from said partition closing said chamber, a disc carried by said element having threads on the periphery thereof, mating thread on the interior of said first member whereby said element is moved along said shaft by rotation of the tubular member about the axis of said shaft to distort said diaphragm.

10. A roller type applicator for liquids according to claim 9 wherein the threads are of limited extent measured axially of the applicator, and the resilient diaphragms urges the disc element to positions for reengaging the threads.

11. A roller type applicator for liquids comprising, a hollow shaft, a member carried by said shaft in fixed relationship therewith, an elongated generally tubular shaped roller member rotatable about the axis of said shaft, a transverse partition within said roller member, means including said partition providing a chamber within said roller member, said roller member having discharge ports from said chamber to the periphery thereof, said shaft having inlet ports from the interior to said chamber, check valve means associated with said discharge ports, check valve means associated with said inlet ports, an element rotatable with said roller member and slideable on said shaft, a resilient diaphragm secured to said element spaced from said partition and secured to said roller member closing said chamber, screw threads carried by said element, mating screw threads on said first member whereby said element is moved along said shaft upon rotation of said roller member about the axis of said shaft to distort said diaphragm.

12. A roller type applicator for liquids comprising, a hollow shaft, a member carried by said shaft in fixed relationship therewith, an elongated generally tubular shaped roller member rotatable about the axis of said shaft, a transverse partition within said roller member, means including said partition providing a chamber within said roller member, said roller member having discharge ports from said chamber to the periphery thereof, said shaft having inlet ports from the interior to said chamber, check valve means associated with said discharge ports, check valve means associated with said inlet ports, a tubular element slideable on said shaft, a resilient diaphragm clamped to said tubular element, an annular shoulder within said roller member, a ring member within the roller member in abutting relationship with the first member, a peripheral portion of said diaphragm positioned between said shoulder and said ring member closing said chamber, resilient means engaging said partition urging said roller member and said shoulder towards said ring member to clamp the peripheral portion of said diaphragm between the shoulder and the ring member whereby the ring member rotates with said roller member, screw threads on said tubular element, mating screw threads on said first member, and means providing a driving connection between said ring member and said tubular element whereby said tubular element is moved along said shaft upon rotation of the roller member about the axis of said shaft to distort said diaphragm.

13. A roller type applicator for liquids comprising, a

liquid guiding tube including a hollow shaft, a member carried by said shaft in fixed relationship therewith, a peripheral bearing surface on said member concentric with the axis of said shaft, an elongated generally tubular shaped roller member having a cylindrical inner surface rotatable on said bearing surface, a transverse partition within said roller member having a central bearing surface rotatable on said shaft portion, means including said partition providing a chamber within said roller member, said roller member having discharge ports from said chamber to the periphery thereof, said shaft having inlet ports from the interior of said tube to said chamber, check valve means for said discharge ports, check valve means for said inlet ports, a tubular element slideable on said shaft portion, screw threads on said element, mating screw threads on said first member, means providing a driving connection between said roller member and said tubular element which slides on said shaft portion during rotation of the roller member, and a distortable diaphragm secured to said tubular element and said roller member closing said chamber.

14. A roller type applicator for liquids comprising, a liquid guiding tube including a hollow shaft, a member carried by said shaft in fixed relationship therewith, a peripheral bearing surface on said member concentric with the axis of said shaft, a generally tubular shaped roller member having a cylindrical inner surface rotatable on said bearing surface, a transverse partition within said roller member having a central bearing surface rotatable on said shaft, means including said partition and a cylindrical bore providing a chamber within said roller member, said roller member having discharge ports from said chamber to the periphery thereof, said shaft having inlet ports from the interior of said tube to said chamber, check valve means for said discharge ports and for said inlet ports, a tubular element slideable on said shaft portion, a piston carried by said tubular element slideable within said bore, screw threads carried by said element, mating screw threads on said roller member, and means restraining said tubular element from rotation during sliding movements thereof whereby said piston is moved during rotation of the roller member about said bearing surface.

15. A roller type applicator for liquids comprising a combination, a tube including a hollow shaft, a generally tubular shaped member supported for rotation about the axis of said shaft, a member carried by said shaft in fixed relationship therewith, a transverse partition within said tubular member, a shell embracing and carried by said tubular member, means including said partition providing a chamber within said tubular member, said tubular member having discharge ports from said chamber to the periphery thereof, said shaft having inlet ports from the interior thereof to said chamber, check valve means associated with said discharge ports, an element slideable on said shaft, means carried by said element spaced from said partition closing said chamber, a disc carried by said element having threads thereon, mating threads on one of said members whereby said element is moved along said shaft by rotation of said tubular member to enlarge the volume of said chamber and draw liquid into the chamber from within said tube, and check valve means preventing upstream movement of the liquid from said chamber during reversed rotation of said tubular member when the liquid is expelled from said chamber through said discharge ports.

16. A roller applicator comprising a tubular handle, an extension on one end of said tubular handle adapted for connection to a liquid supply container, means on the other end of said tubular handle for rotatably journaling a roller applicator sleeve, a porous roller applicator sleeve journaled on said journaling means, pump means positioned within said sleeve, said pump means having an inlet communicating with the interior of said tubular handle and an outlet discharging within said

sleeve, means within said sleeve operably connected to said pump means and operable in response to rotation of said sleeve to operate said pump means to draw liquid through said tubular handle to the interior of said porous sleeve.

17. A roller applicator comprising, a tubular handle, a flexible extension on one end of said tubular handle for receiving liquid from a supply, a tube portion at the other end of said tubular handle, a sleeve shaped tubular member disposed about said tube portion, means carried by the tube portion supporting said tubular member for rotation relative to the tube portion and substantially about the axis thereof, a permeable applicator shell carried by and covering the periphery of said tubular member, pump means positioned within said tubular member, said pump means having an inlet in communication with the interior of said tubular handle and an outlet for discharging liquid from the pump means, means

providing communication from said outlet to the interior of said shell, and means within said tubular member for engaging said pump means operable in response to rotation of said tubular member to actuate the pump means to draw liquid through said tubular handle and to deliver it within said applicator shell.
